CLAIM

I claim the ornamental design for a dog wash station, as shown and described.

DESCRIPTION

FIG. 1 is a perspective view of a dog wash station;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken line showing of the wash tub, back splash, control interfaces and hose structures is for the purpose of illustrating portions of the dog wash station and forms no part of the claimed design.
